UNITED STATES PATENT OFFICE.

ARTHUR R. CURTIS, OF CLEVELAND, OHIO.

AUTOMATIC RELEASEING SWITCH.

Application filed December 28, 1923. Serial No. 683,207.

This invention relates to an automatic releasing switch, and more particularly to a device for automatically opening a circuit upon the passage of a predetermined current therethrough, the device as herein shown being designed particularly for controlling the circuit of fractional horse power motors or other electrically operated devices employing currents of low value.

10 An object of the invention is to provide a compact, simple and inexpensive device having few parts, and these parts of simple construction.

In addition to the features of simplicity, 15 compactness and cheapness of manufacture, the present invention also embodies to a high degree the advantageous features of extreme sensitiveness and reliability in operation.

With the above and other objects in view, 20 the invention may be said to comprise the device illustrated in the accompanying drawings, described in the following specification and particularly set forth in the appended claims, together with such variations 25 and modifications thereof as will be apparent to those skilled in the art to which the invention appertains.

Reference should be had to the accompanying drawings forming a part of this 30 specification in which Fig. 1 is a vertical section taken in a plane which includes the axis of the solenoid and showing the supporting base and switch thereon in elevation; Fig. 2 is a section taken on line 2—2 of Fig. 1; Fig. 3 is a plan view of the base; Fig. 4 is a horizontal section taken on line 35 4—4 of Fig. 1; Fig. 5 is a horizontal section taken on line 5—5 of Fig. 1; Fig. 6 is a horizontal section taken on line 6—6 of Fig. 40 1; Fig. 7 is a vertical section of the base taken on line 7—7 of Fig. 3; Fig. 8 is a sectional detail view showing the blade operating push button and connection to the blade.

Referring to the accompanying drawing, 45 the entire switch releasing mechanism is mounted within a relatively small casing which has a base 1 of insulating material adapted to be attached in vertical position to a suitable support. The base 1 is provided 50 with an outstanding ledge 2 along its edges formed to receive the flanges of an enclosing cover 3 which is attached to the base 1 by means of a post 4 which has a threaded inner end moulded into the central portion of the base, the cover 3 being secured to the outer end of the post 4 by means of a screw

5 passing through the cover and tapped into the end of the post.

The circuit controlling switch is in the form of a knife switch mounted directly 60 upon the base 1 and provided with a blade 6 which is pivoted between the outwardly extending flanges of a pair of angle clips 7 and 8 which are secured to the base 1 by means of the binding screw 9. The superposed flanges of the clips which lie upon the base being held against turning movement thereon by means of a ledge 10 formed on the base. The pivot for the blade 6 is formed by striking up a tongue 11 from the 70 outwardly extending flange of one of the supporting clips. This tongue 11 passes through an opening in the blade 6 and into an opening 12 formed in the other clip. The fixed contact of the switch is formed by a 75 pair of angle clips 13 and 14 which are superposed one upon the other with their outwardly extending flanges spaced sufficiently to permit the blade 6 to be received between them. The angle clips 13 and 14 are secured to the base by means of a binding screw 15. At their ends the outwardly extending flanges are curved outwardly at 16 and 17 to permit the blade to be inserted between the flanges and to guide the blade 85 into the space between the flanges. The outer angle clip 13 is of relatively light resilient sheet metal while the inner angle clip 14 is heavier and less resilient. The blade is thus pressed yieldingly against the 90 heavy contact member 14 in its movement into and out of engagement therewith. The outwardly extending flange of the light clip 13 terminates short of the outer end of the outwardly extending flange of the clip 14 95 so that the break always occurs between the knife and the heavier contact member so that the spring contact member is not damaged by the arcing which occurs when the circuit is broken.

100 The pivoted blade 6 is urged outwardly by means of a spring 18 which is formed of spring wire, the free ends of which are bent outwardly at 19 and secured in recesses in the base 1 and the body of which is bent 105 to substantially circular form, the wire straddling the knife blade and pivot support and being looped under the knife blade in an advance of its pivot. The spring 18 serves to release the switch with a snap whenever the blade is released from its holding means. The upper end of the blade 6 is provided 110

with a T head formed by a hardened steel end piece 20 which is engaged by the hook 21 of a gravity latch member 22 which serves to hold the knife blade in circuit closing position. The latch 22 is in the form of a flat plate and the hoop portion 21 thereof is formed by flanging the outer edge of the plate to provide an inclined edge portion against which the end of the blade strikes in moving to closed position to push the latch out of the way as it passes the hook portion. The inner edge of the latch plate engages in a slot 23 in the base 1 immediately above the fixed contact members 13 and 14, the latch plate being held from movement out of the slot by means of a projection 24 integral with the heavier of the contact members 14 and extending upwardly through a slot in the latch plate 22. The projection 24 serves to loosely retain the latch plate in the slot, and the latch plate swings downwardly by gravity into retaining engagement with the end 20 of the blade. The latch 22 is adapted to be actuated by means of a push button 25 slidably mounted in the casing. The push button 25 has an inner reduced end 26 which is slidably mounted in a recess formed in the base 1 and its outer end is slidably mounted in the cover 3. Adjacent its inner end the push button 25 is provided with a shoulder 27 which engages with an upwardly projecting tongue 28 struck up from the body of the plate 22 so that when the push button 25 is pushed inwardly, the shoulder 27 engages the tongue 28 and the latch 21 is lifted out of engagement with the end 20 of the blade 6, releasing the blade which is then instantly thrown out of engagement with the contact members 13 and 14 by the spring 18. As soon as the push button 25 is released, the latch 22 drops by gravity to a position in which it will engage and retain the blade when the same is again moved to closed position. For returning the blade to closed position, it is provided with a push button 29 in the inner end of which is imbedded a strap 30 which has a laterally bent tongue 31 at its inner end which extends through an opening 32 in the blade. When the push button 29 is pushed inwardly the blade is moved into engagement with the contact and retained in engagement therewith by the gravity latch 22.

55 Mounted alongside the pivoted blade 6 and closely adjacent thereto is a solenoid 33 which is wound about a tube 34 of insulating material. The upper end of the coil is connected to the binding screw 15 and the lower end of the coil is connected to a binding screw 35, the external circuit being connected to the device through the binding screws 9 and 35. Within the tube 34 there is a soft iron core or striker member 36 which has a head portion 37 at its upper

end of insulating material which when the core is actuated by the solenoid strikes against an integral extension 38 of the latch plate 22 which normally rests upon the upper end of the insulating tube 34, the insulated head 37 serving to prevent the plate 22 from sticking to the magnetized core. The core 36 is normally supported upon an adjustable plug 39 which has a threaded engagement with the tube at its lower end. The plug 39 is so positioned that the upper end of the core projects a short distance into the interior of the solenoid. By properly adjusting the plug 39, the core 36 may be so positioned that it will be lifted by the solenoid when a desired predetermined current passes through the solenoid. As the core 36 moves upwardly in the solenoid it moves into the magnetic field so that a progressively increasing force is exerted thereon imparting a sharp acceleration to the core in its upward movement, causing it to strike the extension 38 of the latch plate with a sharp impact, swinging the latch plate upwardly out of engagement with the knife plate which when so released instantly springs to open position breaking the circuit.

Having described my invention, I claim:

1. An automatic releasing switch having a casing consisting of a base and a cup shaped cover adapted to be secured to the base, a switch mounted on the base and having a fixed contact member and a movable contact member biased toward open position, a latch movably mounted on the base and engageable with the movable contact member to hold the same in engagement with the fixed contact, said latch having a bias toward its engaging position, said latch having a laterally extending portion, a vertically disposed tube of insulating material detachably secured at its lower end to the cover and positioned within the same alongside the switch and beneath the laterally extending portion of the latch, a solenoid supported on said tube, said solenoid having a core within the tube which is adapted to be actuated to strike said laterally extending portion of the latch to release the latch upon passage of a predetermined current through the solenoid, and terminals on said base to which the opposite ends of the solenoid winding are connected.

2. An automatic releasing switch having a casing consisting of a base and a cup shaped cover adapted to be secured to the base, a switch mounted on the base and having a fixed contact member and a movable contact member biased toward open position, a latch movably mounted on the base and engageable with the movable contact member to hold the same in engagement with the fixed contact, said latch having a bias toward its engaging position, said latch having a laterally extending portion, a tube of insulating

material which is interiorly threaded at its lower end, means for rigidly securing said tube to the bottom wall of the casing comprising a threaded plug screwed into the lower end of the tube and extending through said bottom wall and a clamping nut on said plug outside the casing, a solenoid supported upon the upper end portion of the tube, and a core within the tube which normally rests on said plug and extends into the lower portion of the winding, said laterally extending portion of the latch lying over the upper end of the tube when the latch is in contact engaging position.

3. An automatic releasing switch comprising a casing having a base adapted to be secured in vertical position upon a support, a knife switch having a vertically disposed blade which is pivoted at its lower end, a spring pressing said blade outwardly, a fixed contact in the form of angle clips secured to the base and having closely adjacent outwardly extending flanges adapted to receive the blade between them, a horizontal groove in the base above the clips, a latch plate having its inner edge seated in the groove, said plate having a slot and one of the clips having an extension passing through the slot and serving to hold the plate loosely in the groove whereby the plate is pivotally supported in the groove, said latch plate extending laterally to one side of the switch and having a retaining portion at its outer edge engageable with the upper edge of the blade, said plate having a lug projecting upwardly therefrom, a push button having a shoulder engageable with the lug whereby the latch plate may be moved by the push button to release the blade, and a magnetically actuated striker adapted to engage the laterally extending portion of the blade.

4. An automatic releasing switch having a casing consisting of a base and a cup-shaped cover adapted to be secured to the base, a switch mounted on the base having a fixed

contact member, a movable contact member biased toward open position, a latch movably mounted on the base and engageable with the movable contact member to hold the same in engagement with the fixed contact, said latch having a bias toward its engaging position, a tube of insulating material mounted in vertical position beneath said latch, said tube being interiorly threaded at its lower end, means for rigidly securing said tube to the bottom wall of the casing comprising a threaded plug screwed into the lower end of the tube and extending through said bottom wall and a clamping nut on said plug outside the casing, a solenoid supported upon the upper portion of the tube, and a core within the tube which normally rests on said plug and extends into the lower portion of the winding.

5. An automatic releasing switch comprising a casing having a base, a knife switch having a blade pivoted to the base, a spring pressing said blade outwardly, a fixed contact in the form of angle plates secured to the base and having outwardly extending flanges adapted to receive the blade between them, a horizontal groove in the base adjacent said clips, a latch plate having its inner edge seated in the groove, said plate having a slot and one of the clips having an extension passing through the slot and serving to hold the plate loosely in the groove whereby the plate is pivotally supported, said latch plate extending laterally to one side of the switch and having a retaining portion at its outer edge engageable with the upper edge of the blade, said plate having a projecting lug, a push button engageable with the lug to move the latch plate in a direction to release the blade, and a magnetically actuated striker adapted to engage the laterally extending portion of the blade.

In testimony whereof, I hereunto affix my signature.

ARTHUR R. CURTIS.
